UNITED STATES PATENT OFFICE.

ALBERT G. BARTON, OF THREE RIVERS, MICHIGAN.

FIELD-ROLLER.

SPECIFICATION forming part of Letters Patent No. 406,078, dated July 2, 1889.

Application filed August 4, 1888. Serial No. 281,972. (No model.)

To all whom it may concern:

Be it known that I, ALBERT G. BARTON, of Three Rivers, in the county of St. Joseph and State of Michigan, have invented a new and useful Improvement in Field-Rollers; and I do hereby declare that the following is a full and exact description of the same, reference being had to the accompanying drawings, and to the letters of reference marked thereon.

10 My invention relates to land-rollers of that kind where a main supporting-frame is employed, having tie-bars which reach through the front and rear beams, and which are provided with eyes on their front ends, to which a draft-bow is attached. Inside of this tie-bound frame are two independent oscillating frames, and to the main frame is a draft beam or tongue attached by V-shaped braces.

Now, the nature of my invention consists 20 in a novel mode of attaching the front and rear journals or trunnions of the inside oscillating auxiliary frame to the main frame, reference being had to the annexed drawings, in which—

25 Figure 1 is a perspective view of a land-roller, showing my improvement applied to it. Fig. 2 is a plan view of the same. Fig. 3 is a longitudinal section showing a drag applied to the main frame. Fig. 4 is a perspective 30 view showing a drag having curved teeth adapted to gently skim over the crushed clods and to even the same, the bar to which the drag-teeth are applied being sufficient to effect the object which I have in view.

35 Referring to the annexed drawings, A designates the main rigid frame; B, tie-bolts extending through the rear piece a' and the front piece a of the said frame. These bolts have eyes b on their front ends, to which is 40 shackled a draft-bow C, having a center draft-loop c in the middle of its length. It will thus be seen that I draw from the posterior beam a' . In addition to these tie-bars, I employ inverted-V-shaped braces G, bolted 45 rigidly to the front and rear beams a a' , and on top of these braces G, I rigidly secure a draft-tongue F, on which is the driver's seat, as shown in Fig. 1.

Inside of the main frame A are two roller- 50 frames E E, bearing the gudgeons of the

rollers D, which may be constructed in any suitable manner. Each inside roller-frame E is provided centrally, fore and aft, with a bearing-plate d , which is a re-enforcing piece, and which is perforated to receive a hooked bolt f . This hooked bolt f is intended to form a part of the bearing-plate d and a journal-connection for the trunnions e . These trunnions e are rigidly bolted to the front and rear transverse beams of the main frame, and are received between the hooked ends of the bolts f and the plates d . It will thus be observed that the inside frames are free to articulate not only about their lateral axes, but that they are also free to articulate about 65 their longitudinal axes. In short, they are hung on a gimbal. By these means it is obvious that the front and rear joints can be adjusted at will, so that the lateral oscillation of each roller-frame is not impeded, or, if by 70 reason of a collection of mud the parts become clogged, the nut on the lower end of the hooked retainers can be loosened, thereby relieving the same.

By reference to Figs. 1, 3, and 4, it will be 75 seen that I employ a hinged drag, which is designed to supersede the old-fashioned bush. It is attached to the frame of the field-roller by means of rods g g , having eyes in their lower ends, as indicated in Fig. 4. The bar 80 J is provided with teeth i , having hooked ends, and it is free to articulate and skim lightly over the crushed ground in rear of the rollers D, for the purpose of lightly harrowing the surface soil.

Having described my invention, what I claim as new, and desire to secure by Letters Patent, is—

In a field-roller of the character described, the combination, with the frame of the machine, of the bar hung therefrom by eyebolts and provided with hook-pointed scratching-teeth, substantially as specified.

In testimony whereof I affix my signature in presence of two witnesses.

ALBERT G. BARTON.
